MAGNETIC ESCAPEMENT FOR TIMEPIECES

Reinhard Straumann, Waldenburg, near Basel,
Switzerland

Application February 4, 1943, Serial No. 474,734

In Germany December 15, 1941

1 Claim. (Cl. 58—116)

It is known to control the running of watch movements and the like by means of a swinging system consisting of a spiral spring and a fly-wheel, which swinging system causes the gear work and consequently the hands to intermittently run off step by step on each swinging period.

All of the swinging systems and escapements used hitherto for this purpose possess frictional parts such as pins, anchor claws, anchor wheel impulse teeth and so on which must be lubricated. The durability of the control power of such run controllers is dependent first of all on the state of lubrication which, as is known, depreciates so quickly in little escapements that the running of the watches is soon impaired.

The main object of the present invention comprises a frictionless controlling system in which the mass of the swinging system is a constitutive part of a magnetic escapement, activating the escapement by its periodical movement.

In order that the invention may be more fully understood, there will now be described by way of example only, and with the aid of the accompanying drawing, a constructional embodiment of the invention.

Fig. 1 is a cross section through the controlling system, while

Fig. 2 is a side-view of the controlling system shown in Fig. 1.

To a block *a* is secured a leaf-spring *b* bearing at its free end a mass *c* which is formed by a little magnetic bar. The spring *b* and the mass *c* form a swinging system designed to control the running of the watch movement in agreement with its swinging frequency. An escapement wheel *d* is provided with two side cheeks *d*¹ arranged laterally on both sides of the magnetic bar *c*, each of these side cheeks carrying an inner and outer circular row of pins *e* and *f*, respectively. The pins *e* and *f* of the side-cheeks project toward each other and on each side-cheek the inner and outer pins are arranged in sets of five. All pins consist of a magnetically permeable material, such as for example soft-iron. The escapement wheel *d* is driven by the watch movement through gearing *g*. On rotating the escapement wheel *d* the magnetic bar *c* is alternately attracted by the inner and outer pins *e* and *f* of the side cheeks so that it oscillates upwardly and downwardly. When the speed of the wheel *d* is so high that the frequency of passage of the pins *e* and *f* corresponds to the swinging frequency of the

swinging system *b*, *c*, the latter will come to a resonance swinging and will oscillate with a strong amplitude.

The driving or moving power transmitted to the wheel *d* must be so high that the wheel *d* tends to run somewhat faster than would be necessary for energising the swinging system *b*, *c*. The magnet *c*, however, acts to restrain the movement of the pins *e*, *f* in their running direction, that is to say the magnetic bar *c* tends to exert a braking action on the pins *f* until it has reached its position corresponding to the greatest amplitude, thus allowing the pins *f* to run relatively freely. After half a swinging period the same operation is repeated between the magnet *c* and the pins *e*. Accordingly, the frequency of passage, i. e. the rotational speed of the wheel *d* is adapted to the frequency of the swinging system *b*, *c* so that there results a constant rotational speed controlled by the swinging system.

The size and dimensions of the parts of the run controller may be chosen so that, for example, the wheel *d* makes one revolution per second and carries on each side cheek *d*¹ five pins *e* and five pins *f* which are offset for half a division relative to each other. If the swinging system is determined in such a manner that it swings with a frequency $Q=5$, it will maintain the wheel *d* at a constant rotational speed $N=1$ per second.

The system according to the present invention has, beside the advantage of a frictionless running, a further advantage in that in such a watch movement there is no necessity for lubrication. If the pins *e* and *f* are properly disposed with respect to the magnetic bar *c*, the swinging system receives a short impulse near its position of rest, as soon as a pin passes the said magnetic bar. Moreover, in the same manner, the alternate braking action of the bar *c* on the pins *e* and *f* also takes place on its passage through the position of rest. The conditions for a constant swinging frequency of the swinging system are thus fully accomplished. The exactitude of the controlling effect is some few seconds within 24 hours, which is sufficient for good watches.

Of course, the above described combined swinging and braking system may also be realized in another way than above explained, so that the present invention is not limited by the described embodiment. Thus, for example, the escapement wheel *d* may be formed as a magnet, where-by the bar *c* may consist of soft iron.

What I claim is:

A frictionless magnetic run controller for watch movements and the like, comprising an oscillating leaf spring fixed at one end, a magnetic mass in form of a bar arranged at the free end thereof and an escapement wheel with two side-cheeks, having each on its inner side two similar rows of radially displaced pins in such position rela-

tive to said magnetic mass as to cooperate therewith in order to energise said spring to successive oscillations and to simultaneously act on the magnetic mass swinging with constant frequency so as to control the rotational speed of the escapement wheel, said magnetic means being disposed intermediate the said side-cheeks.

REINHARD STRAUMANN.
